MAGAZINE FILLING MECHANISM

Norman V. Kuehlman, Milwaukee, Wis., assignor to The National Lock Washer Company, Newark, N. J., a corporation of New Jersey

Original application July 10, 1941, Serial No. 401,804. Divided and this application August 25, 1942, Serial No. 456,043

5 Claims. (Cl. 10—162)

This is a division of my application Ser. No. 401,804 filed July 10, 1941 and issued as Patent No. 2,333,940, November 9, 1943. The invention herein described is for a device for filling successive magazines or quills, which magazines or quills are adapted to hold assemblies of bolt blanks and washers or the like. The invention is shown as embodied in a device for receiving and holding bolt blanks and split-ring lock washers but may be adapted for receiving and storing other devices than these.

The invention is shown as embodied in an assembly machine designed to assemble split-ring lock washers on bolt blanks, but those skilled in the art will recognize that it may be used in other devices and mechanisms.

In the drawings:

Fig. 1 is a perspective view showing the magazine filling mechanism combined with an assembly machine, only part of which is illustrated.

Fig. 2 is a plan view of the quill support.

Fig. 3 is a side elevation showing the locking gate at one end of the quill.

Fig. 4 is a right section taken through 4—4 of Fig. 3.

Fig. 5 is an end view of what is shown in Fig. 3.

Fig. 6 is a section through 6—6 of Fig. 2.

Fig. 7 is a section through 7—7 of Fig. 2.

Fig. 8 is a section through 8—8 of Fig. 2.

Fig. 9 is a plan view of the driving mechanism for the assembly device and control switches.

Fig. 10 is a side elevation of what is shown in Fig. 9.

Fig. 11 is a diagram of the electric circuit for the quill shifting mechanism.

Fig. 12 is a perspective of part of a thread rolling machine and a quill in place thereon.

Fig. 13 is an end view of a quill adapter of a thread rolling machine.

Fig. 14 is a side view of a quill adapted for a thread rolling machine.

In the illustrated arrangement, assemblies, comprising in this embodiment of the invention bolt blanks and split-ring lock washers, are discharged into quills or magazines 109. Each quill includes a pair of parallel angles which form tracks as shown at 110 and 111 (Fig. 4). These are secured by suitable screws 113 to a base 114 extending the length of the quill. A top guide 115, supported on suitable yokes 116, fastened to and spaced along the base 114, is preferably adjustable vertically by means of bolts 115', in relation to the top of the tracks 110 and 111 to

allow for different thicknesses of blank heads and washers.

Pivoted on one end of each quill or magazine is a pivoting gate 117 made in the form of a yoke straddling the top guide 115 and pivoted thereto on bolt 118. A pin 119 limits the upward movement of gate 117. A pin 118' projects outwardly from the side of gate 117 and its function will be described hereafter. When a quill is in position on the quill holder, the open end will be near the end of the discharge track 102 and the closed end, carrying gate 117, near the opposite end thereof.

When a quill is removed from the assembly machine, the gate 117 will be held by gravity in the closed position shown in Fig. 3 and will prevent the assemblies from sliding out from that end of the quill.

A quill shifter and support is shown in Figs. 2, 7, and 8 and comprises a long, channel-shaped framework 120 upon which a pair of quills are designed to rest side by side. The left end of this framework, as viewed in Fig. 2, is equipped with a stop 121, against which the gate end of the quills may be placed. The quill support is pivoted on pin 122 (Fig. 8) carried by a fixed arm 127. On framework 120 above pin 122 is a cross arm 123 with three lugs 124, 125, and 126 thereon, between which a pair of quills may be placed. The right end of the quill support, as seen in Fig. 2, is equipped with a similar cross arm 128 with lugs 129, 130, and 131, between which the right end of the pair of quills may rest. A pair of ears 132 and 133 on arm 128 are adapted to slide on a suitable track 134 and give support to this end of the quill carrier 120.

In operation, the quill support is designed to carry two quills resting thereon on arms 123 and 128 between the lugs arranged on these arms. When the machine is first put in operation, one of the empty quills is positioned in alignment with the discharge track 102 and, when this quill is filled, the quill support automatically shifts the empty quill over in alignment with the track 102 and the full quill may then be removed and replaced with an empty one. When the second quill is filled, the quill support is designed to shift back so that the empty quill, which replaced the first full quill, will then be in alignment with the track 102. This movement of the quill support is accomplished by means of a double solenoid 135, the plunger of which, shown at 136, is connected by a suitable rod 137 to the under side of the quill support

120 (Figs. 2 and 7). Solenoid 135 is of the double type so that it can move the quill support, first in one direction and then in the other direction.

During the actual movement of the quill support, it is necessary to stop the flow of assembled blanks and lock washers momentarily. Without stopping the assembly mechanism shown at A, this is done by means of a finger 138 (Fig. 6) which is mounted on a pivoted arm 139 so as to be superimposed above the track 102 and, when depressed, moves down to tracks 103 and 104. The right end of pivot member 139 is loaded by a coil spring 140 tending to pull this end of the member 139 downwardly, as seen in the figure, and thus raise the finger 138 which is attached to the opposite end of member 139. An arm 140' is designed to engage the under side of arm 139 and limit its downward movement on the spring side thereof. A solenoid 141 is connected by a suitable rod 142 to member 139 between finger 138 and the pivot point 143. The operation of this solenoid will hereafter be described in detail. It will be sufficient to say at this point that immediately before the solenoid 135 is energized to move the quill support either in one direction or the other, the solenoid 141 is energized and moves the stop finger 138 downwardly to the track 102 and thus momentarily arrests the gravity flow of assemblies. As soon as the quill support has moved and the empty quill has taken its position at the end of track 102, the solenoid 141 is deenergized and spring 140 moves finger 138 upwardly and thus the assemblies are released to flow down into the empty quill.

The mechanism for controlling the shifting of the quill support is shown in Figs. 9 and 10 and includes cams operated from shaft 80 on which the assembly device A is mounted. At that end of shaft 80 which is opposite to the end upon which the assembly device is mounted, a pinion 155 meshes with gear 156 on shaft 157. Shaft 157 is mounted on suitable bearings 158 and 159 and carries a worm 160 designed to mesh with a worm wheel 161, which is on a transverse shaft 162 which operates in bearings 163 and 164. On the shaft 162 are mounted four cams 165, 166, 168, and 169 designed to close spring loaded electric switches 170, 171, and 172. The last two cams are mounted 180° apart on disk 167.

The assembly device A and the cam control mechanism for the quill shifter are both mounted or connected to shaft 80 which is carried in suitable bearings 81 and 82. The construction and operation of one form of an assembly device such as that herein called "an assembly wheel" are described in detail and claimed in applicant's Patent No. 2,333,940, issued November 9, 1943. A worm wheel 83 keyed to shaft 80 is adapted to be driven by a worm 84 mounted on a shaft 85 supported in bearings 86 and 87. Shaft 85 carries a handwheel 88 in one end thereof and adjacent thereto a pulley 89 over which runs a belt 90 which is connected to a pulley 91 on the drive shaft of electric motor 92.

Fig. 11 shows the electric circuit diagram for the quill shifting mechanism. Power lines are shown at 220 and 221. These may be connected into any suitable source of power. A hand switch 222 serves to connect and disconnect the electrical part of the quill shifting mechanism with or from the source of power. Shaft 162 is geared to assembly wheel A through suitable reduction gears, as shown in Fig. 9. The shaft carries

cams 165, 166, 168, and 169. Cam 165 operates electric switch 170. Cam 168 operates switch 171, and cams 168 and 169 alternately operate switch 172 on rotation of shaft 162. Switch 172 is connected in series by wire 223 with solenoid 141 and to the power line 220 by wire 224. The other side of solenoid 141 is connected by wires 225 to power line 221. It will thus be seen that solenoid 141 is activated when switch 172 is closed and this is accomplished by cams 168 and 169, twice in each revolution of shaft 162.

Shaft 162 is so geared to assembly wheel A that enough blank assemblies are permitted to move past the stop finger 138 to fill one quill and then switch 172 is closed. The solenoid 141 pulls down the finger 138 to arrest the flow of assembly blanks from the discharge track of the assembly mechanism into the quill.

Switch 171, which is designed to be closed by cam 166, is connected in series by wire 226 with coil 135a of double solenoid 135. The other side of this coil is connected to the power line 220 by wire 227. When cam 166 closes switch 171, coil 135a is activated and moves the quill support from one side to the other. Coil 135b, which forms the other side of the double solenoid 135, is connected in series with switch 170 through wire 228 and the other side of the coil is connected to the power line 221 through wire 229. The other side of switch 170 is connected to power line 220 by wire 230. In Fig. 11, switch 170 is shown closed so that coil 135b of solenoid 135 is activated.

The gear ratio between shaft 80 and shaft 162 is such that 99 assemblies are permitted to slide into an empty quill and then, through the medium of the timing mechanism, solenoid 135 is energized so as to shift the quill support to take the filled quill out of alignment with the discharge track 102 and bring the empty quill into alignment therewith. The stop finger 138 is depressed shortly before and during the shifting operation by solenoid 141 and subsequently released. This is accomplished by the above described timing mechanism.

Figs. 12, 13, and 14 show quill adapter 235 bolted to a thread rolling machine 236 by means of bolts 237.

A full quill 109 is shown inserted in the quill adapter 235 so that the track 110 of the quill is lined up with track 238 of the thread rolling machine. The quill consists of two angularly disposed members 239 and 240 joined together and braced by means of support 241. Member 239 has a channel 242 (Fig. 13) on the upper surface thereof.

Projecting over the edge of this channel are strips 243 and 244 attached to member 239 by bolts 246. The channel and strips form a guideway adapted to receive quill 109. Secured to the upper side of strip 244 is a right angle arm 245. This may be held in place by bolt 246.

Secured to the top of member 245 and projecting at right angles therefrom is a spring finger 247 which is designed to engage pin 118 of the quill gate 117, so as to cause said gate to open by pivoting about bolt 118 when the quill 109 is forced downwardly into the quill adapter 235. Pin 119 on the guard 115 will limit the upward movement of the gate 117. When the gate 117 is moved upwardly as seen in Fig. 12, the blank assemblies are closed by gravity from the quill 109 onto the track 238 of the thread rolling machine.

In operating the assembly machine in con-

junction with a number of thread rolling machines, it has been found convenient for the operator of the assembly machine to remove the full quills and hang them on a convenient rack where they can be readily obtained by the operator of the thread rolling machines. When a quill is hanging on a rack, the open end will be upward and the gate 117 will be closed. When the thread rolling machine operator wishes to insert another quill, it is only necessary for him to remove the empty one from the quill adapter and insert a new one, gate foremost, therein. As the quill is pressed down into its final resting place in the adapter, the spring 247 opens the gate 117 and the assemblies flow into the thread rolling machine. In this manner, the cycle of operation may continue, with the operator of the assembly machine filling the empty quills and placing them on a suitable rack or other receptacle for the use of operator of a thread rolling machine, and the latter in turn returning the empty quills to the operator of the assembly machine.

While I have shown the invention as embodied in a specific form, it is to be understood that various changes in details may be made without departing from the scope of the invention as defined by the appended claims.

I claim:

1. In a machine having assembly means for assembling washers on headed articles, the combination of a discharge track, a quill support adapted to hold a pair of quills side by side, a pivot for said support intermediate the ends thereof, a solenoid for moving said support about said pivot so as to bring the open ends of quills on said support alternately into registry with the end of said discharge track, solenoid-operated means for arresting the flow of assemblies along said discharge track, and means for activating both solenoids each time a predetermined number of assemblies have been made by the machine.

2. In a machine having assembly means for assembling washers on headed articles, the combination of a discharge track, a quill support for a plurality of quills, means for moving said support in relation to the end of said discharge track to bring the ends of successive quills into registry with the edge of said track, means for arresting the flow of assemblies along said track and means for substantially synchronizing the operation of said moving means for the quill support and said arresting means in relation to the assembly means so that both said means

will function each time said assembly means has put together a predetermined number of assemblies.

3. In a machine having assembly means for assembling washers on headed articles, the combination of a discharge track, a quill support for a plurality of quills, a solenoid for moving said support in relation to the end of said discharge track to bring the ends of successive quills into registry with the end of said track, a solenoid-operated arm for arresting the flow of assemblies along said discharge track, switches for controlling electric current to said solenoids, means connected to the assembly means for closing said switches so as to close them each time said assembly means has assembled a predetermined number of washers and articles.

4. In a machine having assembly means for assembling washers on headed articles, the combination of a discharge track, a solenoid-operated arm for arresting the flow of assemblies along said discharge track, a quill support for a plurality of quills, a solenoid for moving said quill support in relation to the end of said discharge track to bring the ends of successive quills into registry with the end of said track, switches for controlling the flow of current to said solenoid, mechanical means operatively connected to the assembly means for operating said switches to cause said solenoid to function each time the assembly means has assembled approximately the number of assemblies which will fill a quill.

5. In a machine having assembly means for assembling washers on headed articles, the combination of a discharge track, a quill support adapted to receive a pair of quills side by side, a pivot for said support, a pair of solenoids adapted to move it in one direction and then in the other so as to bring the ends of alternate quills into registry with the end of said discharge track, means for arresting the flow of assemblies along said discharge track, switches for controlling the flow of current to said solenoids, cams for closing said switches and adapted to close a switch each time the assembly wheel has assembled approximately the number of assemblies which will fill a quill, means for operatively connecting said cams and said assembling means, and means for synchronizing said arresting means on the discharge track with the movement of said quill support so that the discharge of assemblies from said track is stopped during movement of said support.
